CLAIM

The ornamental design for a memory card camera, as shown and described.

DESCRIPTION

FIG. 1 is a front, side and top perspective view of a memory card camera showing my new design, with a lens cover having a built-in flash in a raised and open position;

FIG. 2 is a front elevational view thereof;

FIG. 3 is a rear elevational view thereof;

FIG. 4 is a top plan view thereof;

FIG. 5 is a bottom plan view thereof;

FIG. 6 is a side elevational view thereof from the left of FIG. 2;

FIG. 7 is a side elevational view thereof from the right of FIG. 2; and,

FIG. 8 is a view similar to FIG. 1 but with the lens cover lowered and closed.

FIG. 1

FIG. 2

FIG. 3

FIG. 4

FIG. 5

FIG. 6

FIG. 7

FIG. 8
